UNITED STATES PATENT OFFICE.

CHRISTOPHER B. J. WITMOND, OF SAN ANTONIO, TEXAS, ASSIGNOR OF ONE-HALF TO
FREDERICK G. BLUME, OF SAN DIEGO, CALIFORNIA.

SAFETY LAMP-BURNER.

1,091,417.

Specification of Letters Patent. Patented Mar. 24, 1914.

Application filed December 27, 1912. Serial No. 738,862.

To all whom it may concern:

Be it known that I, CHRISTOPHER B. J. WITMOND, a citizen of the United States, residing at San Antonio, in the county of Bexar and State of Texas, have invented new and useful Improvements in Safety Lamp-Burners, of which the following is a specification.

This invention relates to lamp burners, the object in view being to provide a safety lamp burner embodying, in connection with the usual elements, a self-balancing flame extinguishing cone, which, when the lamp is overturned or subjected to an unusual agitation or shaking, tumbles over the wick and serves to instantly extinguish the flame, thereby preventing serious accident.

With the above and other objects in view, the invention consists in the construction, combination and arrangement of parts, as will be hereinafter more fully described, illustrated in the accompanying drawings, and pointed out in the claim hereunto appended.

In the drawings: Figure 1 is a diametrical section through a lamp burner, showing the present invention applied thereto. Fig. 2 is a similar view taken at right angles to Fig. 1. Fig. 3 is a detail perspective view of the extinguishing cap. Fig. 4 is a detail side elevation, showing the openings which receive the balancing feet of the cap. Fig. 5 is a sectional view similar to Fig. 1, showing a modified arrangement of the extinguishing cap. Fig. 6 is a detail perspective view of the extinguishing cap under the arrangement shown in Fig. 5. Fig. 7 is a detail perspective view of the cap support.

The main body of the burner 1 is of the usual form or construction, being provided with the chimney supporting flange 2, the perforated floor 3, and the wick tube 4, in which the wick of the lamp is mounted and adapted to be slid up and down.

5 represents the usual cone provided with the flame orifice 6.

In carrying out the present invention, the body of the lamp is provided at diametrically opposite points with rectangular openings 7, the same being adapted to receive the oppositely projecting feet 8 of the extinguishing cap, illustrated in detail in Fig. 3.

The flame extinguishing cap comprises a dome-shaped body 9 having a central flame orifice 10 which is materially larger than the corresponding orifice 6 in the cone 5, so as not to interfere in any way with the flame, when such extinguishing cone is in its normal position.

The extinguishing cap is arranged within 60 and under the cone 5, and is of such size that it may readily tip over to one side or the other. The balancing feet 8 are sufficiently wide and flat to rest in the bottoms of the rectangular openings 7, as shown in Fig. 4, so that the extinguishing cap will remain in a central position until the lamp is agitated or shaken, whereupon the cap 9, by reason of its high center of gravity, will tip over to one side or the other, thereby causing the dome-shaped body to snuff out the flame before an accident occurs.

Another form of the device, embodying the same principle, is illustrated in Figs. 5, 6 and 7, in which 11 designates a support for the extinguishing cap, the same being in the form of a rectangular sleeve adapted to fit over and be frictionally retained on the upper end of the wick tube 4. This support is provided with the oppositely and outwardly extending horizontally flat balancing feet 12, which correspond with the feet 8 shown in Fig. 3, being for the same purpose. The cap shown in Fig. 6 is provided with rectangular openings 13 corresponding with the openings 7 in Fig. 4, the openings 13 being designed to receive the balancing feet 12.

By reference to Fig. 5, it will be seen that the outwardly extending balancing feet 12 pass through the openings in the extinguishing cap, and render the action of the tilting extinguishing cap exactly the same as that described in connection with Figs. 1 to 4, inclusive.

What is claimed is:

In combination, a base plate, a wick tube projecting above said base plate, a substantially dome-shaped hood fixed upon said base plate and surrounding said wick tube, said hood being formed at diametrically opposite sides with rectangular openings, a dome-shaped extinguisher, oppositely arranged lugs formed upon the extinguisher and arranged to seat upon the edges of said

opening, said opening being relatively larger than the thickness of said lugs, and right angular feet formed on said lugs, said extinguisher being spaced concentrically from said hood, said feet arranged to frictionally engage the body of said hood at opposite points.

In testimony whereof I affix my signature in presence of two witnesses.

CHRISTOPHER B. J. WITMOND.
